A. ANDERSON

CROWN STRIPPER

Original Filed Nov. 8, 1922

Fig. 3

Inventor
Aetton Anderson
By George E. Val

UNITED STATES PATENT OFFICE.

ANTON ANDERSON, OF NEW HAVEN, CONNECTICUT.

CROWN STRIPPER.

Application filed November 8, 1922, Serial No. 599,717. Renewed January 12, 1925.

To all whom it may concern:

Be it known that I, ANTON ANDERSON, a citizen of the United States, residing at New Haven, in the county of New Haven and State of Connecticut, have invented 55 certain new and useful Improvements in Crown Strippers, of which the following is a specification, reference being had therein to the accompanying drawings.

10 This invention relates to a crown stripper and it is the object thereof, among other things, to provide a simple and effective tool that will remove a crown from a tooth with the minimum labor and without pain 15 to the patient.

To these and other ends my invention consists in the crown stripper having certain details of construction and combinations of parts as will be hereinafter described and 20 more particularly pointed out in the claim.

Referring to the drawings in which like numerals of reference designate like parts in the several figures:

Figure 1 is an elevation of my improved 25 crown stripper;

Figure 2 is a fragmentary elevation thereof looking toward the right of Figure 1; and

Figure 3 is a fragmentary elevation, the 30 parts in section being taken generally upon line 3—3 of Figure 2.

In the practice of my invention I provide a pair of elongated jaws 10 and 11 of the ordinary parallel jaw pliers 12. At the 35 outer end of the jaw 10 is a plate 13 of greater area than the end of the jaw and projects beyond the end and side thereof. This plate may be integral with the jaw or secured thereto as may seem most desirable.

40 The outer end of the jaw 11 is provided with an opening 14 through which projects the shank 15 of a cutter 16, which is held against displacement therein by a screw 17, or the like.

45 Projecting from the head of this cutter is a blade 18, which may be arranged for operation in any one of a number of radial positions about the axis of the shank 15 and there held against movement. The 50 means shown for producing this result con-

sists in forming the end 21 of the shank 15 with a plurality of angular faces, these being shown as eight in number, which project through an opening 19 in the outer end of a plate 20 fastened to the jaw 11.

To vary the radial position of the blade the end of the plate 20 is lifted so as to be out of engagement with the shank 15 and then the latter with the attached cutter is moved to its desired position, when the plate 60 is again released, which again engages and holds the shank against rotary movement.

In practice, the stripper is placed with the plate 13 against the under side of the crown and the jaws opened a sufficient distance to 65 permit the under side of the blade 18 to engage the top of the crown. Then by moving the handles of the tool together as in the ordinary pliers, the blade passes down through the wall of the crown and opens 70 the same so that it may be readily and painlessly removed from the tooth.

By means of the adjustment of the cutter within the jaw 11, the blade can be placed 75 in positions to operate upon any tooth, without pain or inconvenience to the patient, whether in the upper or lower jaw.

Within the scope of the appended claim changes and alterations may be made within 80 my invention, aside from those herein suggested and I would therefore have it understood that I do not limit myself to the exact construction herein shown and described.

What I claim as new and desire to secure 85 by Letters Patent, is:

In a device of the character described having jaws that move parallel to each other, one of said jaws having an opening therethrough near the end thereof at substantially a right angle to the path of movement of the jaw; cutting means, comprising a blade having a cylindrical shank upon one side thereof at substantially a right angle thereto, the outer end of which is angular in cross section, said blade being arranged 95 so that the cutting portion thereof projects beyond the end of the jaw and parallel therewith; means connected with said jaw to prevent accidental endwise movement of the said shank; a spring plate connected 100

with said jaw having an opening therethrough of substantially the same shape in cross section as that of the angular end of said shank and by the engagement of which said blade is held against accidental movement in any of its radial positions about the axis of said shank; and a flat plate con-

nected with the other of said jaws opposite to said blade and of sufficient size to furnish a pressure surface opposite to said blade in any of its adjusted positions.

In testimony whereof, I have hereunto affixed my signature.

ANTON ANDERSON.
